UNITED STATES PATENT OFFICE.

WALTER J. LANGSTON, OF THREE RIVERS, QUEBEC, CANADA.

CENTRIFUGAL CASTING MACHINE.

Application filed September 16, 1922. Serial No. 588,629.

To all whom it may concern:

Be it known that I, WALTER J. LANGSTON, a subject of the King of Great Britain, and resident of Three Rivers, in the Province of Quebec and Dominion of Canada, have invented certain new and useful Improvements in Centrifugal Casting Machines, of which the following is a full, clear, and exact description.

10 This invention relates to improvements in rotary casting machines and the object of the invention is to provide an improved type of machine for casting pipes, tubes or the like, when the article is of considerable 15 length compared with its outside diameter and wall thickness.

In rotary casting machines in use at the present time the metal is poured from one end of the machine into a trough, and from 20 thence into a rotating mould through a spout at the other end of the said trough. This trough is positioned so that it pours the metal on to the side of the mould. In some cases, in casting elongated annular articles 25 the trough, or the mould, or both, move axially with the mould. The metal is thrown against the mould and fed in spiral ribbon form from the spout and the centrifugal speed of the mould is utilized for spreading 30 the metal evenly, making the pipe or annular article of even thickness.

This method is in some respects unsatisfactory as it relies on the centrifugal action for spreading the metal to be cast. This 35 action does not ensure the fusing together of the edges of the ribbon to form a pipe of uniform thickness. Trouble is also encountered in metal cooling in the trough and thus forming obstructions in the trough. If the 40 metal can be fed into the mould in the form of a segment and the feed so arranged that the two adjacent edges of the segment overlap and fuse together to give an evenly distributed layer of metal, it is obvious that an 45 improvement in casting pipes will be achieved. It is also obvious that if the trough can be cleaned directly after or during the operation of the apparatus the efficiency of the apparatus will be increased.

50 In my invention the molten metal is delivered to the machine in a ladle fitted with a valve adapted to be controlled to regulate the flow or feed. The ladle is placed over a spout which leads into a trough which feeds 55 the metal into a rotating mould. The spout by its particular construction cleans the

travelling trough as it travels from end to end of the rotating mould. The spout also provides for a regular pressure on the feed and thereby ensures a regular flow of metal 60 into the mould. The flow of metal is such that metal is delivered in segmental form, that is with a heavy feed in the centre of the pouring and a lighter feed on the outside edges. The speed of the spout is so arranged that the thin edges of one layer overlap the thin edges of the next layer, fuse together and form a layer of even thickness. The end of the trough is formed or shaped 65 to obtain this result.

70 Referring to the drawings;

Figure 1 is a side elevation of the apparatus showing the rotating mould and the feeding mechanism.

Figure 2 is a cross sectional view of the 75 trough.

Figure 3 is a fragmentary elevation of the trough.

Figure 4 is a fragmentary plan of the trough showing the end of the trough cut 80 to ensure an even feed.

Figure 5 is a view showing the spout, the trough and a sectional elevation of the mould with a pipe being cast.

Figure 6 is an end elevation of the feeding mechanism.

Figure 7 is an end elevation of the rotating mould.

Referring more particularly to the drawings, 12 designates a valve which can be operated by a handle 13 for regulating the feed from a ladle 11. The ladle 11 is placed on the frame of the machine 14 and is held in position by the metal bands 15 mounted on the frame 14 and riveted thereto, together with a circular strap 16 riveted to the ladle. A spout 17 is used for feeding the metal into the travelling trough 18. The end of said spout is shaped to fit into the inside of the trough and is of such shape 90 that in passing along the trough it cleans it and leaves an even surface behind it. Guide pulleys 19 and a guide 20 riveted or bolted to the frame 14 are provided to ensure even and efficient working of the trough 18. A cooling space 21 is provided in the trough. The construction may be made as shown in Figures 2, 3, 4, that is, a pipe split at the centre the one half being placed inside the other, and the sides welded, sealed, riveted or 95 fused together forming a trough of crescent section with an air space 21 between the 100 105 110

outer surface of one half and the inner surface of the other, or it may be made in cast form. Referring to Figure 4, the end of the trough 43 is cut at an angle of about 45° to give a heavy feed at the centre of the cut and a light feed at its edges. The feed is so arranged that, for one revolution of the rotating mould, the travelling trough moves through a distance to allow the thin edges of the feed to overlap and fuse together and thus give an even feed. On the lower side of the trough a rack 22 is cut or fitted to gear with a pinion 23 which carries the trough in or out according to requirements. A train of gears 24, 25, 26 and 27 mounted on the shafts 28 and 29 revolving in suitable bearing bolted to the frame 14, and operated by a motor 30 is used for operating the trough within the mould. A friction clutch 31 operated by a handle 32 may be provided to ensure easy engagement and operation of the said gears. The frame 14 can be mounted on a truck 33, so that the machine can be moved rapidly and conveniently from one mould to the other on the wheels 34. The mould 35 rests on the rollers 36 which are mounted on a frame 37. The mould is rotated by a motor 38 driving a pair of gear wheels 39. The geared wheels 39 drive the rollers 36 mounted on and keyed to the shafts 40 revolving in the

journal bearing 41 bolted to the frame 37. One of the gears is mounted on and keyed to the driving shaft 40.

Figure 5 shows a partly cast pipe 42 in the mould 35.

The operation of the machine is as follows. The molten metal is delivered into the machine in the ladle 11. The valve 12 is opened by pulling the handle 13 and the metal flows into the spout 17 and from thence into the trough 18. The trough 18 at the beginning of the process is placed as far into the mould as required and immediately pouring takes place the mould 35 is rotated and the trough 18 is gradually withdrawn at a speed necessary to produce a pipe of required thickness.

Having thus described my invention, what I claim is:—

In a rotary casting machine, the combination of a rotary mould, a pouring trough, means for inserting the trough in said mould and then gradually withdrawing the mould, said trough having a canal open at both ends and a cooling chamber situated below the canal and being equipped with a pouring end bevelled and thereby adapted to feed the metal to the lowest part of the mould.

In witness whereof, I have hereunto set my hand.

WALTER J. LANGSTON.
